SPINNING TOP

Nathan Laing, New York, N. Y.

Application September 4, 1937, Serial No. 162,443

2 Claims. (Cl. 46—66)

This invention relates to new and useful improvements in a spinning top.

More specifically, the invention is characterized by a top body which is free to spin in the air and having a bottom peg upon which it may spin and a stem axially mounted on the top of the body provided with a cord windable upon the body which may be used to spin the top.

Still further the invention is characterized by the provision of several buttons mounted on the end of the stem which are adapted to rattle and make noises while the top is in motion.

As a further object of this invention it is proposed to construct the top body substantially frusto-conical in shape with the apex at the bottom thereof, and concave grooved sides on which the cord may be wound for providing the momentum to spin the top.

Still further a means is proposed for eccentrically holding the buttons in various adjusted positions on the end of the stem for controlling the amount of noise they will make when the top is spinning.

Another object of the invention is the construction of a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is an elevational view of a spinning top constructed according to this invention.

Fig. 2 is a sectional view taken on the line 2—2 of Fig. 1.

Fig. 3 is a sectional view taken on the line 3—3 of Fig. 1.

Fig. 4 is an enlarged sectional view of a portion of Fig. 1.

Fig. 5 is a plan view of Fig. 4 showing details of the construction of the buttons per se.

The spinning top, according to this invention, consists of a top body 10 having a bottom peg 11 upon which it may spin when suitably thrown with a cord 12 which is adapted to be wound on the body 10. A stem 13 is axially mounted on the top of the body 10, and a pin 14 is mounted on the end of the stem 13 and several buttons 15 adapted to rattle are mounted on the pin 14.

The top body 10 consists of a piece of material substantially frusto-conical in shape with

its apex 10^a at the bottom thereof. It is provided with a flat top 10^b and concave sides 10^c. The concave side 10^c is provided with a spiral groove 16 upon which the cord 12 is adapted to be wound. The peg 11 is constructed of heavy wood or metal and is adapted to be set into the apex end 10^a of the body 10, and the top is adapted to spin on a point 11^a of the bottom peg 11.

The stem 13 consists of a wooden peg set into the top face of the top body 10, and the pin 14 extends into a hollow formed in the top end thereof. This pin 14 consists of a body portion 14^a upon which the buttons 15 are mounted. Near the top the pin 14 is provided with a bulged portion 14^b which continues into a narrow portion 14^c, which in turn continues into the head portion 14^d. The string 12 is adapted to have one of its ends 12^a tied around the narrow portion 14^c of the pin 14 between the bulged portion 14^b and the head 14^d so that the pin 14 may rotate together with the top body 10 while the entire device is being held in a vertical position by the string 12. The outer end 12^b of the string 12 is provided with a button 17 which may be gripped for the purpose of holding same when spinning the top.

A means is provided for axially urging the pin 14 inwards for clamping the buttons together at certain pre-determined pressures best suited to rattle the buttons. This means includes a hollow 13^a formed in the outer end of the stem 13. A cover element 18 is secured across the top of the recess 13^a and is provided with an opening 19 through which the pin 14 extends. The interior end of the pin 14 is provided with a head 20 and a spring 21 is coaxially mounted on the inner portion of the stem 14^a and acts between the cover element 18 and the head 20 to urge the pin 14 into a position in which the buttons will assume a position best suited for rattling. The covered element 18 prevents the head 20 and the spring 21 from the recess 13^a.

The buttons 15 are constructed of bone or other noise making material and a means is provided for eccentrically pivotally holding them in position on the body portion of the pin 14. This means comprises a radial slot 22 formed in the body of each button 15, and a wavy spring 23 is mounted within the slot and is adapted to engage the sides of the pin 14 in order to fixedly and pivotally hold the pin in position within the waves. Thus, the position of the buttons 15 with relation to the stem 14 may be controlled by pulling the buttons to var-

ious positions on the pin 14 as permitted by the wavy spring 22.

The operation of the device is as follows:

- 5 The string 12 is brought down along the side of the top body 10 until it reaches somewhat below the apex 10^a. It is then wound on the concave sides of the body 10 and engages the groove 16 in order to hold it in position thereon. The button 17 is then gripped and the top is thrown 10 into the air, so that the top spins in the air. The top may also be lowered by holding the button 17 of string 12, so that the point 11^a of the bottom peg 11 will engage upon a flat surface to permit the top to spin in an upright position.
- 15 The string 12, still gripped, is held so that it will assist in maintaining the top in a substantially vertical position. When this string is not wound on the top body 10, it assumes a position indicated by the dot and dash lines 12' in Fig. 1.
- 20 While the top is spinning the wobbling of the top will cause the buttons 15 to hit against each other, making various sounds. When the top has lost its momentum, and it is desired to re-spin the top, the cord 12 is again wound on the 25 top body 10 and the above procedure is repeated.
- 30 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:—

1. A spinning top, comprising a top body having a bottom peg upon which it may spin when suitably thrown with a cord wound on said body, a stem axially mounted on the top of said body, a pin mounted on said stem, and several buttons, adapted to rattle, mounted on said pin, said buttons being constructed of bone or other noise 10 making material and being provided with a means for eccentrically holding said buttons in position upon said pin.

2. A spinning top, comprising a top body having a bottom peg upon which it may spin when suitably thrown with a cord wound on said body, a stem axially mounted on the top of said body, a pin mounted on said stem, and several buttons, adapted to rattle, mounted on said pin, said buttons being constructed of bone or other noise 20 making material and being provided with a means for eccentrically holding said buttons in position upon said pin, said means comprising a wavy slot formed in the body of said buttons and through which said pin extends, and a spring 25 extending the distance of said slot and conforming with said slot and being adapted to engage the side of said pin for holding the buttons in various adjusted positions upon said pin.
